COLLAPSIBLE SMOKING PIPE

Thomas M. Bills, 8810 Littlewood Road,
Baltimore, Md. 21234

Filed July 12, 1973, Ser. No. 378,495

Term of patent 14 years

Int. Cl. D27—02

U.S. Cl. D85—8 A

FIG. 1

FIG. 2

FIG. 3

FIG. 4

FIG. 5

FIG. 6

FIG. 7

FIG. 8

FIG. 1 is a perspective view of a collapsible smoking pipe showing my new design;

FIG. 2 is a right end elevational view;

FIG. 3 is a left end elevational view;

FIG. 4 is a perspective view in open condition;

FIG. 5 is a right end elevational view thereof;

FIG. 6 is a left end elevational view thereof;

FIG. 7 is a bottom plan view thereof; and

FIG. 8 is a perspective view of a collapsible smoking pipe showing a modified form of my new design, the unseen portions being the same as those depicted in FIGS. 6 and 7.

I claim:

The ornamental design for a collapsible smoking pipe, substantially as shown and described.
